APPARATUS FOR PRODUCING OIL FROM
SUBSURFACE DEPOSITS

Eiley A. Aucoin, Overton, Tex., assignor to Standard Oil Development Company, a corporation of Delaware

Application November 19, 1937, Serial No. 175,356

3 Claims. (Cl. 103—232)

The present invention is directed to an apparatus for producing oil from oil wells.

In the art of producing oil from oil wells it has become common practice to aid the movement of the oil from the formation to the surface, when the pressure in the formation is not sufficiently great to maintain a constant flow of oil to the surface, by injecting gas into the oil at various points along the conduit connecting the formation to the surface. Another expedient which has been adopted is the borehole pump. The latter is expensive and involves operating difficulties. The former loses its usefulness when the formation pressures drops below a certain level.

According to the present invention, both the gas lift principle and the pump principle are employed. In the apparatus of the present invention a chamber is arranged in the borehole, a head of oil is permitted to build up in the chamber by virtue of the formation pressure until the head becomes sufficiently great to open a valve against the pressure of a supply of high pressure gas introduced into the well. At this time the connection between the chamber and the formation is broken and the high pressure gas forces the oil out of the chamber to the surface until the head of oil in the chamber is reduced below a certain predetermined value when the supply of high pressure gas is shut off and the chamber is again fluidly connected to the formation. Means are provided for preventing the high pressure gas from acting on the formation.

The nature of the present invention will be better understood from the accompanying drawing in which Figure 1 is a vertical section through a well containing the arrangement of the present invention;

Fig. 2 is a detail view, partly in section, of a modified form of the arrangement of the present invention; and

Fig. 3 is a detail view of an element shown in Fig. 2; and

Fig. 4 is a longitudinal section of one type of valve which may be employed in connection with the arrangement of the present invention but the specific construction of which forms no part of the present invention.

Referring to the drawing in detail, 1 designates the earth having an oil bearing sand 2, connected to the surface by borehole 3. Arranged in the borehole is a casing 4 having a closed upper end provided with a pressure gauge 5 and a gas inlet 6 controlled by a valve 7. Projecting through the top of the casing is a pipe 8 terminating near

the lower end of the casing in an enlarged chamber 9 having a constricted lower open end in which is arranged a seat for a check valve, such as a ball valve 10. A tube 11 is suspended in chamber 9 from pipe 8 to which it is joined by a weld 12 or a suitable bushing. Mounted outside the pipe 8 and above or below chamber 9 is a packer 13 adapted to seal off the upper portion of the casing from the formation.

Outside the casing pipe 8 is provided with suitable valves and with a pressure gauge 14.

Arranged on pipe 8 below the junction of pipe 8 and tube 11 is a valve 15 of the gas lift type which works on one side against gas in the upper part of the casing and on the other side against oil in the chamber 9. This valve can be one of the many available types of conventional gas lift valves operated by a pressure differential. Its specific construction forms no part of the present invention. A valve capable of operating on any desired differential, which will be dictated by the formation pressure, will be selected. For example, the conditions of the well may make it advisable to employ a valve operating on a differential of about 100# per sq. in. in conjunction with a gas supply at 300# per sq. in. In this case the valve will open to admit gas into chamber 9 when the head of oil in the chamber amounts to 200# per sq. in. As soon as the valve opens the pressure in chamber 9 will increase due to the inrush of high pressure gas and will keep the valve open until the pressure in chamber 9 is reduced to below 200# per sq. in. by the removal of the head of oil therefrom.

In operation, oil flows into chamber 9 and thence into pipe 8 until the head of oil above valve 15 is sufficient to cause it to open and admit high pressure gas into chamber 9. This causes the oil to flow downwardly in chamber 9, thereby closing the ball valve 10 and sealing off the formation. The high pressure gas forces the oil contained in the pipe and in chamber 9 to the surface. As soon as the head of oil above valve 15 is reduced to a predetermined value valve 15 will close, ball valve 10 will open and the cycle will be repeated.

As previously stated and as is apparent, the packer 13 can be above or below the chamber 9. This packer prevents the high pressure gas from acting on the formation and thereby decreasing the flow of oil from the formation.

While chamber 9 may in some cases be omitted, it is a very important part of the combination. Chamber 9 makes it possible for a larger amount of oil to accumulate for a given head. This is

important because it increases the ratio of the volume of oil to the volume of gas admitted through valve 15 and thereby minimizes the possibility of the occurrence of slippage of the gas past the oil. Without chamber 9 such slippage may occur and greatly reduce the efficiency of the combination.

The arrangement shown is extremely useful in regulating the flow of oil from producing wells. 10 By adjusting the distance between the chamber 9 and the oil sand, the time required to build up a sufficient head of oil above valve 15 to open it can be regulated, thereby regulating the rate of production. This feature is a very marked advantage 15 since it reduces the amount of attention that must ordinarily be given the producing well.

In Fig. 2 an arrangement is shown in which the gas inlet valve is arranged inside the chamber 9 instead of on pipe 8. Arranged in pipe 8 above chamber 9 is a plug 16 having a radial passage 17 which opens at the center of the lower face of the plug into the chamber 9. Arranged around the face of plug 16 are a plurality of longitudinal passages 18 for conducting oil from chamber 9 to pipe 8. Suspended in chamber 9 from passage 17 is pipe 11. Attached to pipe 11 by a screw-thread connection is a gas lift valve 19 shown in detail in Fig. 4.

Referring to Fig. 4, the essential elements of the gas lift valve are a gas inlet 20, a gas chamber 21, a gas outlet 22 and a main plunger 23 having a cone shaped end 24 adapted to be seated on one end of gas outlet 22. Plunger 23 is carried by a sleeve 25 and is normally held in open position by a spring 26. The end of sleeve 25 near the head of the plunger is provided with ports 27 for permitting the passage of gas from chamber 21 to the outlet 22 which in turn is connected to chamber 9 by port 35.

At the other end of sleeve 25 a second plunger 28, of smaller diameter than the inside of the sleeve, is slidingly mounted. It is adapted to be seated on a valve seat 29 at the end of an annular opening 30 which is in free communication with the exterior of the valve, that is, the oil chamber 9 through passage 36. Plunger 28 is normally held off of this seat by a spring 31. It is also adapted to seat at the end of a chamber 32 which is connected to gas chamber 21 by a series of ports 33. Chamber 32 is also connected by a by-pass 34 to the chamber in which the rear end of plunger 23 rides.

In Fig. 4 the parts of the valve are shown in the position they assume before the valve is associated with the combination shown and when the valve is in use under a sufficient oil head to set it into operation. With the parts in the position shown the valve is connected in place as shown in Fig. 2. As soon as the upper end of the casing is filled with high pressure gas this gas enters the valve through inlet 20 and fills chamber 21, entering chamber 32 through ports 33. The pressure of the gas on plunger 28 forces it off its seat at the end of chamber 32 against the force of spring 31 to its seat 29. This permits the high pressure gas to flow through by-pass 34 to the rear of plunger 23 which is thereby forced onto its seat at the end of gas outlet 22 against the force of spring 26.

When oil enters chamber 9 it flows through the opening 36 at the lower end of the valve to the rear of plunger 28. When the head of oil in chamber 9 becomes sufficiently great it forces plunger 28 off its seat 29 to its seat at the end

of chamber 32, thereby cutting off the gas supply to by-pass 34. The high pressure gas already contained behind plunger 23 is forced out by the action of spring 26 through by-pass 34 and through the annular space 30 and passage 36 into chamber 9. Simultaneously valve 24 is unseated from the end of chamber 22 permitting high pressure gas to flow through outlet 22 into chamber 9 through port 35. The parts remain in this position until the head of oil is dissipated whereupon the gas pressure again forces plunger 28 to its seat 29 and the cycle of operations begins again.

It is apparent that many changes may be made in the arrangement illustrated and described above without departing from the scope of the present invention. It may be mentioned here that the utilization of a plurality of gas lift valves along pipe 8 in the conventional manner is contemplated in the practice of the present invention.

The nature and objects of the present invention having been thus described and illustrated what is claimed as new and useful and is desired to be secured by Letters Patent is:

1. An arrangement for producing oil from a subsurface formation through a borehole connecting the formation to the surface comprising a casing in the borehole, a packer in said casing intermediate its ends sealing off the upper portion of the casing from the formation, a pipe in the borehole extending from the surface to below the packer and arranged for fluid connection with the formation, an enlarged portion in said pipe forming a chamber, a tube of reduced cross sectional area arranged in said pipe and extending from above the chamber into the chamber and terminating adjacent the bottom thereof, the upper end of said tube having its outer surface connected to the inner surface of the pipe in a fluid tight manner and opening into said pipe, a check valve at the lower end of said chamber, a conduit at the upper end of said chamber connecting said chamber to the casing above said packer, means for supplying high pressure gas to the casing above said packer and a valve arranged in said conduit adapted to be normally held in closed position by said high pressure gas to prevent flow of gas to said chamber, and to be opened upon the attainment of a predetermined head of liquid in said pipe.

2. An arrangement for producing oil from a subsurface formation through a borehole connecting the formation to the surface comprising a casing in said borehole, a packer in said casing intermediate its ends for sealing off the upper end of the casing from said formation, means for applying high pressure gas to the upper end of said casing, a pipe arranged in said casing from the surface to a point below said packer, an enlarged portion in said pipe forming a chamber, a plug in said pipe above said chamber having a radial passage having one of its ends opening into the casing above the packer and the other of its ends terminating in such chamber, a tube connected to said latter end and depending into said chamber, a valve arranged in said tube for establishing fluid connection between the casing and the chamber, said valve being of a type which is adapted to be normally held in closed position by said high pressure gas to prevent flow of said gas to said chamber, and to be opened upon the attainment of a predetermined head of liquid in said pipe, a check valve at the lower end of said chamber and lon-

itudinal passages in said plug for establishing a fluid connection between said chamber and said pipe.

3. An arrangement for producing oil from a subsurface formation through a borehole connecting the formation to the surface comprising a casing in the borehole, a packer in said casing intermediate its ends sealing off the upper portion of the casing from the formation, a pipe in 0 the borehole extending from the surface to below the packer and arranged for fluid connection with the formation, an enlarged portion in said pipe forming a chamber, a conduit for establishing

fluid connection between said pipe and one end of said chamber, a conduit connecting the other end of said chamber with the upper portion of said casing above said packer, means for supplying high pressure gas to the portion of the casing above the packer, a valve arranged in said last mentioned conduit adapted to be normally held in closed position by said high pressure gas to prevent flow of said gas to said chamber and to be opened upon the attainment of a predetermined head of liquid in said pipe and a check valve at the lower end of said chamber. 5 10
